(57) **CLAIM**

I claim the ornamental design for a metal detector with ball magnet, as shown and described.

DESCRIPTION

FIG. 1 is a front perspective view of an embodiment of a metal detector with ball magnet;

FIG. 2 is a top plan view of the embodiment shown in FIG. 1;
FIG. 3 is a bottom plan view of the embodiment shown in FIG. 1;

FIG. 4 is a back side elevational view of the embodiment shown in FIG. 1;

FIG. 5 is a front side elevational view of the embodiment shown in FIG. 1;

FIG. 6 is a cross sectional view taken along line 6—6 of the embodiment shown in FIG. 2;

FIG. 7 is a cross sectional view taken along line 7—7 of the embodiment shown in FIG. 2;

FIG. 8 is a right side elevational view of the embodiment shown in FIG. 1; and,

FIG. 9 is a left side elevational view of the embodiment shown in FIG. 1.
